UNITED STATES PATENT OFFICE.

HARRY A. HOKE, OF ALTOONA, PENNSYLVANIA

LOCOMOTIVE SMOKE-LIFTER.

1,130,738.

Specification of Letters Patent.

Patented Mar. 9, 1915.

Application filed January 2, 1914. Serial No. 809,819.

To all whom it may concern:

Be it known that I, HARRY A. HOKE, a citizen of the United States of America, residing in Altoona, in the county of Blair and State of Pennsylvania, have invented 5 certain new and useful Improvements in Locomotive Smoke-Lifters, of which the following is a true and exact description, reference being had to the accompanying drawings, which form a part thereof.

10 My present invention relates to railway locomotives, and has for its object to provide simple and effective means for lifting the smoke issuing from the smokestack of a 15 locomotive sufficiently high above the locomotive to prevent it from obscuring the engine crew's view along the right of way.

20 My invention is devised to overcome a rather serious difficulty which has been experienced with modern locomotives. In such a locomotive the smokestack itself, cannot project much above the top of the boiler, proper on account of the size of the latter, and because of this fact, and the long length 25 of the boiler, the smoke issuing from the smokestack is not carried high enough at times to prevent it enveloping the locomotive cab, thereby making it difficult or impossible for the engine crew to distinguish 30 signals or other objects along the right of way.

The various features of novelty which characterize my invention are pointed out with particularity in the claims annexed to 35 and forming a part of this specification. For a better understanding of the invention, however, and of the advantages possessed by it, reference should be had to the accompanying drawings and descriptive matter, 40 in which I have illustrated and described one form in which my invention may be embodied.

45 Of the drawings: Figure 1 is an elevation, partly in section, of a locomotive equipped with my invention; Fig. 2 is an enlarged 50 plan view of a portion of the top of the smokestack of the locomotive shown in Fig. 1; and Fig. 3 is a section on the line 3-3 of Fig. 2.

55 In the drawings, A represents the locomotive, and A' the smoke box at the front end of the locomotive. C represents the usual exhaust nozzle discharging upwardly into the smoke box, and B represents the screen provided to prevent the passage of cinders

into the smokestack E. As shown, a ring blower D is mounted on top of the exhaust nozzle C, and is supplied with live steam at times when the engine is at rest or drifting to create the desired draft, and, under some conditions, may be operated when the engine is working to supplement the action of the exhaust, discharged through the nozzle C, on the draft.

The smokestack E, as shown, is formed 65 with a flanged portion E' fitting against the boiler shell and a portion E² extending into the boiler and terminating somewhat above the exhaust nozzle C. At its upper end the stack E is formed with a hollow bead. 70 From the annular passage E³ in the hollow bead lead upwardly directed passages E⁴ which are inwardly inclined toward the axis of the smokestack. Live steam is supplied to the passage E³ through the pipes F and 75 H from the steam dome A² of the locomotive. The flow of steam through the pipe F is controlled by the valve G located in the locomotive cab A³, and a valve I is shown as located in the locomotive cab to control 80 the passage of steam through the pipes H and J to the blower D.

In the use of my invention steam is supplied to the annular passage E³ at the top 85 of the smokestack whenever this is necessary or desirable to prevent the smoke from obscuring the engine crew's vision along the right of way. When steam is thus supplied 90 to the passage E³, the jets of steam issuing from the upwardly directed and inwardly inclined nozzle passages E⁴ impinge against the gaseous products issuing from the smokestack in such manner as to carry these products well above the locomotive. It is to 95 be observed that these jets of steam do not interfere with, but, on the contrary, directly augment the action of the other agencies tending to create a draft through the smokestack; and that the means for producing these jets are so disposed that they do 100 not interfere with the free flow of the gaseous products through the smokestack.

Having now described my invention, what I claim as new and desire to secure by Letters Patent, is:

1. In a locomotive, the combination with the locomotive smokestack of means for discharging steam at the top of said stack in upwardly and inwardly directed jets disposed around the circumference of the stack 110

at the top thereof adapted to lift the smoke issuing from the stack well above the upper end of the latter.

2. In a locomotive, the combination of a locomotive smokestack provided at its upper end with a chamber surrounding the passageway for smoke, and with nozzle passages leading upwardly and inwardly therefrom so that steam supplied to said chamber will issue from said passages in jets impinging against and lifting the body of gaseous products issuing from the smokestack well above the upper end of the latter, and means for supplying steam to said chamber from the locomotive boiler comprising piping and a controlling valve located in the locomotive cab.

3. In a locomotive, the combination with the locomotive smokestack provided at its upper end with a chamber surrounding the passageway for smoke and with a plurality of small size nozzle passages leading upwardly and inwardly therefrom, and inclined toward the stack axis so that steam supplied to said chamber will issue from said passages in jets impinging against and lifting the body of gaseous products issuing from the smokestack well above the upper end of the latter, and means for supplying

steam to said chamber from the locomotive boiler comprising piping and a controlling valve located in the locomotive cab.

4. In a locomotive, the combination of a locomotive stack provided at its upper rim with an annular steam chamber surrounding the smoke passage through the stack and having a series of small orifices so directed that steam jets issuing therefrom will focus at a point in the axis of the stack some distance above the top of the latter so that the body of gaseous products issuing from the smoke-stack will be lifted well above the upper end of the latter, and a steam pipe connecting said chamber to the boiler.

5. In a locomotive, the combination with the locomotive smokestack of means for discharging steam at the top of said stack in upwardly directed jets inwardly inclined somewhat toward the axis of said stack and uniformly distributed about the latter, said jets being adapted to lift the smoke issuing from the stack well above the upper end of the latter.

HARRY A. HOKE.
